Hugh Donley INVENTOR

BY R. S. & H. Lacey
ATTORNEYS.

UNITED STATES PATENT OFFICE.

HUGH DONLEY, OF CANNELTON, PENNSYLVANIA.

CAR-COUPING.

SPECIFICATION forming part of Letters Patent No. 549,633, dated November 12, 1895.

Application filed September 16, 1895. Serial No. 562,665. (No model.)

To all whom it may concern:

Be it known that I, HUGH DONLEY, of Cannelton, in the county of Beaver and State of Pennsylvania, have invented an Improved 5 Car-Coupler, of which the following is a specification.

This invention relates, generally, to car-couplers, and particularly to that class thereof known as the "Janney" type; and the objects 10 of this invention are, first, to provide an improved form of pin-operating mechanism; secondly, to provide improved means for automatically throwing the knuckle outward when the pin is raised to unlock said knuckle.

With these objects in view the invention consists in the peculiar construction of the several parts and the novel manner of combining or arranging them, such as will be fully described hereinafter, and then pointed out 15 in the claims.

In the drawings forming a part of this specification, Figure 1 is a perspective view of a car-coupler embodying my invention. Fig. 2 is a vertical longitudinal section. Fig. 3 is a horizontal longitudinal section. Fig. 4 is a sectional view on the line 4-4 of Fig. 3. Fig. 5 is a detail perspective view of the knuckle. Fig. 6 is a detail perspective view of the pin, and Fig. 7 is a detail perspective view of the 20 lever operated by the pin to open the knuckle.

In carrying out my invention I employ the draw-head A, which in general contour is substantially the same as the draw-head of the ordinary Janney coupler—that is, it comprises the rigid jaw a and the movable knuckle a'. The movable knuckle a' is provided, as usual, with the inwardly-extending arm B, which is adapted to be engaged by the vertical sliding pin C for the purpose of locking said knuckle, 25 and in connection with said knuckle and pin I provide a knuckle-opening lever D, which is pivoted within the draw-head to one side of the arm B and operated by the upward movement of the locking-pin, so that when said pin is raised to unlock the knuckle said lever D 30 will be operated by said pin to throw the knuckle open. The pin, which is most clearly illustrated in Fig. 7, is the square upper portion c and the flat narrow portion c', said upper portion terminating in a shoulder c'', which is cut away at c''' for the purpose of permitting the end of the arm B to pass through beneath,

said arm being beveled or cut away, as shown at b, which engages the cut-away portion c''' and automatically raises the pin until said 35 arm has passed beyond the shoulder, when said pin is dropped by gravity and automatically locks the knuckle. The arm B is also grooved upon its upper and lower faces near the forward end, as shown at b', which grooves 40 receive the guides b'', formed in the draw-head, which guides insure a positive movement of the knuckle, said knuckle being pivoted in the draw-head in the usual or any approved manner. 65

In order to raise the pin for the purpose of releasing and opening the knuckle, I employ a novel form of mechanism, which consists of a lever E, located within the hollow draw-bar, said lever being pivoted upon a rod or bolt E', passing transversely through said draw-head, the forward end of said lever working in a mortise e' in the pin, and the rear end of said lever is pivotally connected to a second lever F, which is also located in 70 the draw-bar, fulcrumed upon a rod or shaft f, and the forward end of said lever projects into the draw-head alongside of the pin and rests upon a lug or finger g of the vertical moving lifting-rod G, which slides in a vertical groove e. 75

By means of the above-described construction it will be readily seen that by raising the lifting-rod the lever F will be raised at its forward end and drops at its rear end, and 80 inasmuch as this lever F is connected at its rear end to the rear end of the lever E the forward end of said lever E will be raised and with it the pin C. 85

Now in order to open the knuckle automatically at the same time the pin releases it, I employ a knuckle-opening lever D, before referred to, which is pivoted within a recess formed in the side of the draw-head, and by referring to Fig. 7 it will be seen that 90 said lever comprises a forwardly-curved nut d and lug d' at the rear end, which lug has a curved or beveled face d'' for a purpose presently described, and the enlarged portion d'', through which the pivotal bolt d' passes, in 95 order to pivotally secure said lever within the recess in the draw-head.

The pin C is formed with a curved or sloping edge c'', which engages the curved or

beveled face d^2 of the lug d' , so that as said pin is raised the curved surfaces will engage each other, the rear end of the knuckle-opening lever-rod forced inward and the forward 5 end thrown outward, and as said rod seats in a recess a^3 , formed in the knuckle, said knuckle will be thrown open and the car will be ready for coupling. In order to render the operation of the lever quicker and easier, I 10 form the knuckle with a curved boss a^4 , which contacts with a curved portion d^5 of the knuckle-opening lever, whereby the purchase or bearing surface between the knuckle and lever is increased.

15 In order to permit the insertion of the peculiar-shaped pin C, the draw-head is constructed with a similarly-shaped opening, and in order to close the said opening at the upper end I employ a cap-piece or block II, which is 20 held in place by a pivotal bolt of the knuckle-opening lever and completely covers the opening in the draw-head; and I further utilize this block or cap-piece and make it act as a stop for the pin by placing a horizontal lug 25 or finger h in the side of the pin C, which lug or finger engages the bottom of the cap-piece or block II, and thus limits the upward movement of the pin C.

By means of the peculiar arrangement of 30 the levers E and F located in the shoulder, the movement of the pin is rendered quick and certain, and the quickness of said pin serves to positively actuate the knuckle-opening lever, so that it will be seen that I provide 35 a car-coupling embodying these automatic features, which will operate in a wholly efficient and satisfactory manner.

Having thus described my invention, what I claim as new, and desire to secure by Letters 40 Patent, is—

1. In a coupling of the class described, the combination, with the draw-head, and knuckle, of the coupling pin, the operating levers arranged within the draw-bar, and the lifting rod for operating said levers, substantially as 45 shown and described.

2. In a coupling of the class described, the combination with the draw-bar, and head, and knuckle, of the coupling pin, the levers E, and F, arranged within the draw-bar, and the 50 lifting rod G, for operating the said levers, substantially as shown and described.

3. In a coupling of the class described, the combination, with the draw-head, of the knuckle, having the rear end of its locking arm 55 beveled or curved, and a recess or seat upon the inner face of said locking arm, and the boss or enlargement adjacent to said recess or seat, the uncoupling lever having a curved forward end, and the beveled lug at the rear 60 end, and the coupling pin having a square upper end, a flat lower end with intermediate locking shoulder, an inclined operating surface, said locking shoulder adapted to engage the locking arm of the knuckle, and the inclined surface being adapted to engage the beveled or curved lug of the opening lever, substantially as shown and described.

4. In a coupling of the class described, the combination, with a coupling pin, having 70 square upper end, and flat lower portions of the cap or block II, and the lug or finger h, all arranged and adapted to operate substantially as shown and described.

In testimony whereof I affix my signature 75 in the presence of two witnesses.

HUGH DONLEY.
